UNITED STATES PATENT OFFICE.

CHARLES A. DUNCAN AND ALFRED NELSON, OF WALLACE, IDAHO.

BALL MILL.

1,412,390.

Specification of Letters Patent. Patented Apr. 11, 1922.

Application filed August 6, 1921. Serial No. 490,437.

To all whom it may concern:

Be it known that we, CHARLES A. DUNCAN and ALFRED NELSON, citizens of the United States of America, residing at Wallace, in 5 the county of Shoshone and State of Idaho, have invented certain new and useful Improvements in Ball Mills, of which the following is a specification.

This invention relates to an improvement 10 in ball mills and more particularly to the provision of an improved arrangement of helix in the outlet trunnion of such a mill.

In the ball or pebble mills commonly in 15 use a helix is usually formed in the outlet trunnion, the function of which is to prevent the balls or pebbles in the mill from passing out through the outlet trunnion and through which trunnion the water and mill feed are discharged. However, in order for the water 20 and mill feed to pass out over the helix such water and mill feed has to accumulate in considerable quantity and it is frequently the case that the balls or pebbles pass out along with the mill feed.

25 It is the primary object of the present invention to provide a helix of such a nature as will permit the escape of the water and the mill feed and will effectually prevent the escape of the balls or pebbles.

30 Further objects and advantages of the invention will be set forth in the detailed description which follows.

In the accompanying drawing:

Fig. 1 is a view in side elevation of the 35 outlet trunnion of a ball or pebble mill and the bearing in which it is mounted;

Fig. 2 is an enlarged sectional view illustrating a slightly modified form of trunnion; and

40 Fig. 3 is an end elevation of the construction shown in Fig. 2.

Like numerals designate corresponding parts in all of the figures of the drawing.

The invention resides in disposing in the 45 outlet trunnion 5 of a conventional ball or pebble mill, a helix 6, the outer periphery of said helix being spaced from the inner periphery of the trunnion to leave a space 7 between the helix and the trunnion through

50 which the water and mill feed may find its way but through which the balls or pebbles in the mill cannot pass. It is immaterial what particular means are employed to hold the helix in spaced relation to the wall of the 55 trunnion. As one means of accomplishing this result, we have illustrated set screws 8.

It is to be understood that the invention is not limited in this respect and that any desired means may be employed for spacing the helix from the wall of the trunnion.

60 In Fig. 1 we have illustrated a fragment of a conventional ball mill wherein the trunnion 9 is mounted to rotate in a suitable bearing 10. Such a construction as this is quite common and it is to be understood that 65 we do not claim, broadly, the idea of including a helix in the outlet trunnion of a ball mill, because this we know to be old. However, so far as we are aware, it is new to mount a helix in the outlet trunnion of a 70 ball mill in such manner that the helix will always tend to feed the balls back into the mill, if they tend to escape and to space such helix from the inner periphery of the outlet trunnion in the manner herein described. 75

An additional advantage of the arrangement recited is that the balls or pebbles may be fed into the mill whenever desired by merely inserting them in the outlet trunnion and letting them come within the range of 80 the action of the helix.

It is to be understood that the invention is not limited to the precise construction set forth but that it includes within its purview whatever changes fairly come within either 85 the terms or the spirit of the appended claims.

Having described our invention, what we claim is:

1. The combination with the outlet trunnion of a ball mill, of a helix disposed therein in the outer periphery of which lies in spaced relation to the inner periphery of the trunnion, leaving a passage for material through the trunnion between the inner periphery of 95 the trunnion and the helix, said helix being open at its sides between its convolutions to establish free communication between the interior of the helix and said passage

2. A structure as recited in claim 1 in 100 combination with spacing elements carried by the helix and engaging the wall of the trunnion for holding said helix in spaced relation to said wall.

3. The combination with the outlet trunnion of a ball mill, of a helix disposed therein and means for holding the helix in spaced relation to the inner periphery of the trunnion to leave an opening between the helix and trunnion substantially entirely there-around and from end to end of the trunnion 110 to permit the passage of material from the

interior of the mill to the exterior thereof between said helix and the wall of the trunnion, said helix being open at its sides between its convolutions to establish free communication between the interior of the helix and said first named opening.

4. In combination a ball mill having an outlet element of tubular formation, a helix disposed in said outlet element and means for holding the helix in spaced relation to the inner periphery of the said element to leave an opening between the helix and element substantially entirely around the helix and from end to end of the element to permit the passage of material from the interior of the mill to the exterior thereof be-
- 10
- 15

tween said helix and the wall of the element, said helix being open at its sides between its convolutions to establish free communication between the interior of the helix and the first named opening.

In testimony whereof we affix our signatures in the presence of two witnesses.

CHARLES A. DUNCAN.
ALFRED NELSON.

Witnesses as to Charles A. Duncan:

H. J. HULL,
J. M. PEARCE.

Witnesses as to Alfred Nelson:

CHARLES MOONEN,
A. P. MITCHELL.
